PLAYING BALL

Filed June 15, 1927

Inventor

HOWARD C. EBERT.
By His Attorney
Frank H. Lent

UNITED STATES PATENT OFFICE.

HOWARD C. EEBERT, OF BROOKLYN, NEW YORK, ASSIGNOR TO A. G. SPALDING & BROS.,
OF NEW YORK, N. Y., A CORPORATION OF NEW JERSEY.

PLAYING BALL.

Application filed June 15, 1927. Serial No. 198,885.

This invention relates to playing balls of the type in which an inflatable bladder is protected by a cover of wear-resistant material. In such balls it is a common practice to provide a small aperture in the cover by means of which access may be had to the inflating valve carried by the bladder.

It is an object of the present invention to furnish an improved closure means for the inflating aperture to prevent the entry of mud and dirt into the valve.

While a preferred embodiment has been disclosed for purposes of illustration, it should be understood that various changes may be made in the structure without departing from the spirit and scope of the invention as hereinbefore set forth and claimed.

In the drawings:

Fig. 1 is a perspective of a ball embodying the invention showing a pump connected thereto.

Fig. 2 is a cross section through the cover and bladder at the inflating stem.

Fig. 3 is an enlarged plan of the structure of Fig. 2, parts being broken away.

Fig. 4 is a section showing a modification.

Fig. 5 is a section through the closure member.

Referring to the drawings more particularly, reference numeral 10 indicates the outer protective covering of the playball and 11 refers to an aperture in the cover. Numeral 12 is applied to a piece of heavy rubber secured to the inner side of the cover about the aperture 11. This rubber piece has a flap 14 cut therefrom, the main part of the flap being severed from the piece 12 along a line corresponding to the contour of the aperture 11, but one side of the flap being left integral with the piece 12 as indicated at 15 in Fig. 3.

A second piece of heavy rubber 16, having an aperture 17 of a shape similar to that of aperture 11, is positioned below the piece 12. A piece of leather 18 lies below rubber piece 16 and carries a threaded bushing 19 adapted to receive the inflating stem of the bladder. A finishing piece 20 covers the end of the bushing, and a row of stitching 21 secures all the inside pieces to the cover 10.

The inflatable bladder 22 carries a valved

inflating stem 23, the exterior of which carries threads mating with those of the bushing 19. In assembling the ball the bladder is inserted into the cover through a laced opening in a well-known manner, and the stem 23 is then screwed into the bushing 18. After the laced opening in the cover has been closed the ball is ready for inflation. This is accomplished by turning the flap 14 outwardly as indicated in Figs. 1 and 5, and the pump is then connected to the stem 23 in the usual way. When the inflating has been accomplished and the pump is disconnected, the flap 14 returns to its normal position covering the opening 11, in which position it effectively prevents passage of undesirable foreign matter into the inflating stem.

In some instances it may be found desirable to form the inner rubber piece 16 with an aperture smaller than that through the flap-carrying piece 12, thereby forming a shoulder 24. Fig. 4 which prevents inward movement of flap 14. Fig. 4 also shows a different type of valve stem 25 held in place by a layer 26, all of the inner layers being held together and to cover by cement instead of stitching. A bladder is attached to stem 25 in any convenient manner.

I claim:

1. A playing ball comprising a cover having an aperture therein, a piece of rubber secured to the inner side of the cover, and a flap partially punched from the rubber piece and adapted to normally close the aperture.

2. A playing ball comprising a cover having an aperture therein, an inflatable bladder within the cover and having an inflating stem aligned with the aperture, and a piece of resilient material attached to the inner side of the cover, said resilient piece carrying a flap which is partially punched from the resilient piece and adapted to normally cover the inflating stem.

3. A playing ball comprising a cover having an aperture therein, a piece of rubber secured to the inner side of the cover and carrying a flap which is partially punched from the resilient piece and adapted to normally close the aperture, an inflating stem, means adjacent to the aperture for anchoring the

inflating stem in position registering with the aperture, and an inflatable bladder in communication with the inflating stem.

4. A playing ball comprising a cover having an aperture therein, a piece of resilient material secured to the inner side of the cover, a flap carried by a resilient piece and adapted

to normally close the aperture, and a piece of material secured to the inner side of the resilient piece and having a shoulder preventing inward movement of the flap.

In testimony whereof I affix my signature.

HOWARD C. EBERT.
